FISH LURE

James F. Gondeck, 21 N. Barrett, Niles, Mich.

Filed Mar. 11, 1960, Ser. No. 59,700

Term of patent 14 years

(Cl. D31—4)

FIG. 1

FIG. 2

FIG. 3

I claim:

The ornamental design for a fish lure, substantially as shown.
